(57) **CLAIM**

The ornamental design for a connector adapter, as shown and described.

DESCRIPTION

FIG. 1 is a perspective view of a connector adapter showing our new design;

FIG. 2 is a front view thereof;

FIG. 3 is a rear view thereof;

FIG. 4 is a top view thereof;

FIG. 5 is a bottom view thereof;

FIG. 6 is a left view thereof;

FIG. 7 is a right view thereof; and,

FIG. 8 is another perspective view thereof.

The trademark “ACON” forming part of the claimed design is a registered trademark (Reg. No. 2,157,036) of Advanced-Connectek Inc. (Taiwan Corporation).

The ornamental for a connector adapter, as shown and described.
